FRITZ ECKHARDT AND MAX HOHNEKAMP, OF EISENACH, GERMANY.

ELECTRIC INCANDESCENT LAMP.

Application filed May 5, 1927, Serial No. 189,140, and in Germany September 27, 1926.

This invention relates to electric incandescent lamps which are suitable to be used in series with one another and of the kind in which a shunt is permanently connected to the ends of the incandescent filament, which shunt is made of a material which is not conductive as long as the normal voltage of the lamp is applied to its ends and which becomes conductive as soon as a higher voltage is applied thereto.

An arrangement of this character which is considered to be in the nature of a safety device ensures that when several lamps are connected in series with one another to the supply circuit, the current flows only through the filaments of the lamps as long as the incandescent filaments are in good condition. However, when an incandescent filament is destroyed, the whole of the supply voltage is applied to the ends of the corresponding shunt, which becomes conductive so that the other lamps of the series continue to be incandescent. The shunt is preferably made so that when it has become conductive its resistance is substantially equal to the resistance of the incandescent filament that has been destroyed, so that the conditions of the other lamps, which continue to be incandescent, remain substantially unaltered.

It has been found that the substances which have hitherto been used for such shunts do not possess the necessary constancy or they are difficult to manipulate or to mount.

The present invention consists in making the said shunt of such chemical compounds of metals, as they are found in form of ores, viz., sulphides or oxides and mixtures thereof, either in the natural form or in a calcined state or as a mixture thereof. These substances are used either in the form of solid pieces or in small particles, such as in the form of grains or powder, either alone or mixed with small particles of other conductive or non-conductive substances or with small particles of such substances mixed with one another.

Instead of ores or of substances obtained from ores by calcining, use may be made of other substances having the same chemical composition, which are produced by synthesis from the component parts.

When use is made of ores in the form of sulphides, we employ more particularly those having a metallic lustre or pyrites. Galena

the oxides, metallic iron oxide (Fe_2O_3) may be mentioned by way of example.

All the substances above referred to are especially suitable for carrying the invention into effect because they are very insensitive to atmospheric influences and moisture. Further, they have a high limit, that is to say, the voltage at which these substances suddenly pass from the non-conductive to the conductive state is rather high. For this reason, when substances of this character are employed, they do not require the same great care as the substances which have hitherto been used; more particularly they need not be arranged loosely in their containers but they can be firmly pressed in, which also contributes towards increasing the constancy of the shunts thus produced. It is entirely immaterial at which points these shunts are arranged between the ends of the filaments. They may be mounted in the holder or in the socket of the lamp, or even in the lamp itself. However, they are preferably mounted in the lower part of the lamp (in the lamp foot) in such a manner that they connect directly to leads in the lamp.

The invention also relates to another arrangement for increasing the reliability of lamps by means of shunts or safety devices, the conductivity of which is varied by an increase in the voltage and it consists in this that the lamp is provided with two incandescent filaments which are connected together by means of a shunt of the character above referred to in such a manner that upon one of the filaments being destroyed, the current will flow through the shunt and the second filament.

The two arrangements may be combined together in such a manner that upon the two filaments being destroyed, the other lamps which are connected in series therewith will continue to be incandescent.

With this object in view, a filament which has been provided with a shunt between the two ends of the filament is provided with a second incandescent filament which is connected at one end with one end of the first incandescent filament and at its other end with the other end of the first incandescent filament through a second shunt, which is also of such a character that it is not conductive for the normal voltage of the incandescent filament but becomes conductive as soon as the said voltage is increased. By suitably choos-

ing the materials and dimensions of the second shunt, the voltage required for rendering the latter conductive can be made smaller than the voltage that is required for rendering conductive the shunt arranged across the ends of the first incandescent filament.

In an arrangement as just referred to, when the first filament is burnt through, first of all the second shunt becomes conductive so that 10 the second incandescent filament is brought into the circuit whilst the first shunt is still non-conductive. However, when the second incandescent filament is destroyed, the whole 15 of the voltage is applied for a moment to the first shunt and bridges over the ends of the incandescent filament, although the other lamps which are connected in series with this lamp continue to be alight.

The invention is illustrated by way of example 20 in the accompanying drawings, in which

Figure 1 shows the application of the invention to a lamp with one incandescent filament,

Figure 2 its use in connection with a lamp having two incandescent filaments, whilst

Figure 3 is a simplified form of lamp provided with two incandescent filaments.

Referring to Figure 1, *a* is a bulb of the 30 lamp, *b* the lower narrower part thereof, viz, the neck, *c* is the foot, into which the leads *d* of the incandescent filament *i* are fused.

The incandescent filament *i* is dimensioned 35 for a voltage of 14 volts. The hollow part of the foot is closed up by a stopper *f* of suitable material, such as asbestos, and a layer of cement *g*. A layer *e* of grains of galena is placed in the hollow space which is left free 40 between the fused end of the foot *c* and the stopper *f* and through which the connecting wires *k* pass to the leads *d*, so that the said layer makes direct contact with the connecting wires *k*. In the construction shown in this 45 figure, the whole space is not completely filled up with the layer *e* so that an air space *h* is left free; however, the layer may be arranged to completely fill the whole of the hollow space, more especially in the case of galena.

50 *l* is a glass bottom, *m* a bottom contact, *n* a screw-threaded sleeve, these three parts constituting together the socket of the lamp. The two connecting wires *k* are connected to the bottom contact *m* and the screw-threaded 55 sleeve respectively.

The operation of the lamp hereinbefore described is as follows: When the lamp is connected in series with other lamps to a source of current, the whole of the current will flow 60 along the following path:—*n*, *k*, *i*, *k*, *m*, whilst no current will pass through the shunt formed by the layer *e* of galena since the 14 volts will not be sufficient for this purpose. However, when the filament *i* is destroyed, the 65 full voltage of the source of current (for in-

stance, 110 volts) will first of all be applied to the two wires *k* and this voltage will be sufficient to render the shunt conductive. When the galena has thus become conductive, it will acquire when properly dimensioned, 70 for instance for the properly chosen distance between the two conducting wires *k* and *k*₁, a resistance which is approximately equal to the resistance of the filament when incandescent, so that a voltage of 14 volts will again be applied to the contacts *m* and *n* with the result that the voltage conditions for the other lamps are the same as before the filament *i* was destroyed.

In Figure 2, which illustrates a lamp without a socket, use has been made of the same references as have been mentioned with respect to Figure 1 for denoting similar parts. In this form of construction a second filament *i*₀ is provided in addition to the filament *i*, 80 which second filament is also dimensioned for a voltage of 14 volts, one end thereof being connected to the same lead as the one end of the filament *i*. However, the other end of the filament *i*₀ is connected to a separate lead *d*₀, 85 which in its turn is connected to a separate connecting wire *k*₀ which is not led outside the lamp but terminates in the space which is filled with galena, the arrangement being such that the distance between *k*₁ and *k*₀ is smaller 90 than the distance between *k* and *k*₁.

The operation of the lamp just referred to is as follows: When the lamp is connected in series with the other lamps to a source of current, for instance altogether seven lamps 100 across a voltage of 110 volts, the current first of all flows along *k*, *i*₀, *k*₁, because the voltage of 14 volts between the wire *k*₁ and the wire *k*₀ is not sufficient to render conductive the galena between *k*₁ and *k* or between *k*₁ and *k*₀. 105 However, when the filament *i*₀ is destroyed, the whole of the voltage, viz, 110 volts, is momentarily applied on the one hand between the wires *k*₁ and *k* and on the other hand between the wires *k*₁ and *k*₀. This voltage is 110 sufficient to render the galena conductive and since the distance between *k*₁ and *k*₀ is smaller than the distance between *k*₁ and *k*, the part between *k*₁ and *k*₀ will become conductive first, so that the filament *i* will now 115 be inserted into the circuit and the same conditions will apply as before the destruction of the filament *i*₀, so that a voltage of approximately 14 volts will again be applied between *k* and *k*₁, which voltage is not sufficient to 120 render the shunt between the wires *k* and *k*₁ conductive. However, when also the filament *i* is destroyed, the whole of the voltage, viz, 110 volts, will again be applied momentarily to the wires *k* and *k*₁ and, as in the 125 first form of construction, the current will pass from *k* to *k*₁ through the galena, so that although this lamp is no longer in operation, the other lamp will continue to remain incandescent.

The lamp illustrated in Figure 3 is similar to the lamp illustrated in Figure 2, the difference being that the connecting wire k is surrounded by an insulation p where it passes through the layer of galena e . As long as the current passes through the filament i , a voltage of about 14 volts will be applied to k_1 and k_0 so that no current will pass through the galena e between these two filaments. However, when the filament i is destroyed the voltage of the supply circuit will be applied to k_1 and k_0 and the mass of galena between the two filaments will become conductive and the current will flow from k through the filament i_0 and k_1 and the mass of galena e to k_0 .

What we claim is:

1. An electric incandescent lamp having an incandescent filament and a shunt permanently connected to the ends of the said filament and consisting of a sulphide ore, said shunt being non-conductive when the normal voltage of the lamp is applied thereto, but becoming conductive when a higher voltage is applied to it.

2. An electric incandescent lamp having an incandescent filament and a shunt permanently connected to the ends of the said filament and consisting of galena, said shunt being non-conductive when the normal voltage of the lamp is applied thereto but becoming conductive when a higher voltage is applied to it.

3. An electric incandescent lamp having two leading contacts, a filament across the said two contacts, a second incandescent filament connected at one end to one of the said leading contacts and a shunt permanently connected between the second end of the second incandescent filament and the second leading contact, the said shunt consisting of ore and being non-conductive when the normal voltage of the lamp is applied thereto but becoming conductive when a higher voltage is applied to it.

4. An electric incandescent lamp having two leading contacts, an incandescent filament connected across the said two contacts, a second incandescent filament which is connected at one end to the one leading contact, a shunt which is permanently connected between the second end of the second incandescent filament and the second leading contact and is made of such a substance and is so dimensioned that it is not conductive when the normal voltage of the lamp is applied thereto but becomes conductive when a higher voltage is applied to it, and a second shunt which is permanently connected between the ends of the first incandescent filament and is made of such a material and is so dimensioned that it is not conductive when the normal voltage of the lamp is applied thereto but becomes conductive when a voltage is applied to it which is higher than the voltage that renders the first shunt conductive.

5. An electric incandescent lamp having an incandescent filament and a shunt connected to said filament, said shunt consisting of an ore and being non-conductive when the normal voltage of the lamp is applied thereto but becoming conductive when a higher voltage is applied to it and having sufficient resistance on becoming conductive to prevent the shunt from functioning substantially as a dead short circuit.

6. An electric incandescent lamp having an incandescent filament and a shunt connected to said filament, said shunt consisting of a compound and being non-conductive when the normal voltage of the lamp is applied thereto but becoming conductive when a higher voltage is applied to it and having sufficient resistance on becoming conductive to prevent the shunt from functioning substantially as a dead short circuit.

In testimony whereof we have signed our names to this specification.
